Charles H. Warwick, Philadelphia Co. Pa. Letters
Patent No. 199. dated August 30th 1848.

The Schedule referred to in these Letters Patent
and making part of the same.

To all whom it may concern: Be it known that
I, Charles H. Warwick of the County of Philadelphia state
of Pennsylvania have invented or produced a design of a
new cast iron Bottom & Top plates, frame, and door, to be
used together, for a design for Air Tight wood stoves, and
I hereby declare that the following is a full and exact des-
cription, figure 1. bottom plate, fig. 2. Top plate, Fig 3 frame
for door, Fig 4. door, Fig 5. Ventilator for door. The annex-
ed Drawing is a correct representation of the same.

Your petitioner claims to be the original inventor
or producer of the combination of the ornamental figures con-
stituting one design as herein set forth.
